UNITED STATES PATENT OFFICE.

EDWARD P. CALDWELL, OF HARVEY, ILLINOIS.

TRACTION ATTACHMENT FOR VEHICLES.

1,322,228.

Specification of Letters Patent.

Patented Nov. 18, 1919.

Application filed August 22, 1918. Serial No. 250,956.

To all whom it may concern:

Be it known that I, EDWARD P. CALDWELL, a citizen of the United States, and a resident of Harvey, in the county of Cook and State 5 of Illinois, have invented certain new and useful Improvements in Traction Attachments for Vehicles, of which the following is a specification, reference being had to the accompanying drawings.

10 Tractors are ordinarily provided with wheels the rims of which have bolted to the outer face thereof projecting lugs or cleats that dig into the ground over which the machine moves to prevent slipping, as is well understood. In some instances, however, as when passing over a paved or improved road, such devices on the wheels are not only unnecessary but are objectionable on account of the damage that they 15 do to the road paving or other surfacing. Indeed, the travel of machines with wheels so equipped over improved roads is prohibited in many communities. It is the object of my invention to provide the wheels 20 of such a machine with radially-movable lugs or cleats that can be projected when desired, and to the extent desired, or be retracted so as to be entirely out of contact with the surface of the ground or roadway,—and also to provide means whereby 25 such projecting and withdrawing of the lugs or cleats will be at all times wholly under the control of the driver of the machine, such operations being capable of being performed without stopping the movement of the machine. It is a further object 30 of the invention to provide wheels so equipped with such radially-movable lugs or cleats with an improved resilient tire, some of the securing members therefor being slotted to allow the projection there- 35 through of the lugs and acting to brace such lugs to a greater extent than if they were braced only by the walls of the slots in the wheel-rim through which the lugs 40 also project. I accomplish these objects by the means shown in the drawings and hereininafter particularly described. That which I believe to be new and desire to 45 cover by this application will be set forth in the claims.

In the drawings.

Figure 1 is a plan view of a portion of the frame-work of a tractor with its two rear driving wheels connected therewith, one of said wheels being shown in plan

and the other being in section,—the radially-movable lugs or cleats carried by the wheels being represented in their withdrawn or inoperative position. The means by 60 which the lugs or cleats are simultaneously moved outward by the driver are also represented in this view;

Fig. 2 is a side elevation of one of the wheels with the lugs or cleats thereof projected into operative position, a small portion of the rim and tire of the wheel being in section;

Fig. 3 is a central section through the wheel with the parts in position as in Fig. 2;

Fig. 4 is a perspective view, partly broken away, of the wheel and the means for compelling a projection of the lugs or cleats,—the view being taken from the inner side of the wheel, and the lugs or cleats being 75 shown projected;

Fig. 5 is a detail, being a perspective view of a portion of the resilient tire;

Fig. 6 is a detail, being a perspective view of one of the slotted strips that secure the 80 tire in place and through the slot in which one of the lugs or cleats projects; and

Fig. 7 is a similar view of one of the other tire-securing strips.

Referring to the several figures of the 85 drawings: 10 indicates a portion of the framework of a tractor of any ordinary construction. 11 indicates an axle affixed to the rear portion of the framework 10 and having rotatably mounted on each of its 90 ends a wheel—the two wheels being identical in construction. 12 indicates the wheel rim, 13 the hub thereof and 14 a heavy web that lies centrally of the rim and connects the rim and hub together. Such rim and 95 web are preferably formed integral. The web is shown as lying alongside of an annular flange 15 formed on the hub, and is bolted to such flange by a series of long bolts 16, said bolts each having formed on 100 it in the construction shown at about its center a head 17 which lies against the face of the flange 15, and by tightening up the nuts 18 on the screw-threaded ends of such bolts the web and hub member are tightly 105 clamped together. Each of the bolts 16 is much longer than is necessary for merely clamping the web and hub together, and they are so made in order to serve as supports for a sliding member hereininafter described. The roller bearings 19 are shown as interposed between the hub and the shaft,

- 20 indicates a cap placed over the end of the hub, such cap being secured as shown by the bolts 16 which pass through an annular flange of the cap. 21 indicates an internal gear secured upon the inner face of the rim 12 near its inner edge, by means of which power is applied to the wheel through a gear 22 fast on the end of a drive shaft 23 as usual.
- 10 24 indicates a series of lugs or cleats each being in the form of a heavy flat plate. These cleats are arranged radially of the wheel and each is movably fitted in one of a series of slots 25 formed through and transversely of the rim 12. In line with each slot 25 in the rim there is formed in the web 14 a radially disposed slot 26. These slots 26 also receive the lugs or cleats 24, such slots being of sufficient depth to permit the lugs 20 or cleats to be drawn in out of operative position—that is, below the outer contacting portions of the tire hereinafter mentioned. To the inner edge of each lug or cleat is secured one end of a contractile 25 coiled spring 27, the other end of which, in the construction shown, is attached to a link 28 that is secured to one of the bolts 16. Such springs normally tend to draw the lugs or cleats inward to the limit permitted by the slots 26 that they respectively enter. Inasmuch as each lug or cleat when in its outward or operative position has a considerable portion lying within its slot 26 it will be very effectually braced by 30 the walls of such slot and by reason thereof the strains imposed against its face as it digs into the earth will not damage it. By reason of the thickness of the web 14 a very substantial support is thus given to the lug 35 or cleat. 29 indicates a resilient tire applied to the rim of the wheel, and preferably resting in a shallow recess in such rim as shown. As shown, the tire used is formed with alternate ridges and grooves extending 40 transversely, the parts being so proportioned that one of the said grooves of the tire comes opposite each slot 25 and in such grooved portion there is formed a slot registering with the underlying groove in the 45 rim. In each of said slotted grooves is secured a cross-strip 30 whose under face is curved to fit the groove and through which cross-strip is a slot 31 in registry with the underlying slots in the rim and tire. These 50 cross-strips 30 therefore serve not only as a means for aiding in holding the tire in place, but they serve as an additional bracing means for the lugs or cleats to bear against when projected into operative position. 32 indicate other cross-strips that rest in other and smaller grooves of the tire and are employed as additional holding means for the tire.
- 33 indicates a head, annular in shape as 60 shown, said head in the construction shown
- having an opening centrally therethrough in which is fitted a thimble 34 the edges of which are turned at right angles to form front and rear flanges which lie snugly against the opposite faces of the annular head, although not so snugly as to prevent the required smooth turning of the head on the thimble. This thimble is slidably mounted upon the axle member 11, and to the flange lying against the inner face of the head 33 is securely riveted an annular plate 35. Through the head 33 there are formed a number of holes corresponding in number to the number of the long bolts 16 and of a size to permit such bolts to have a sliding fit therein. The thimble 34 and plate 35 while slidably mounted upon the axle 11 will be prevented from turning with respect to such axle by means of a feather or key, as shown in Fig. 4. 36 indicates a flexible connection, preferably a short piece of steel cable, that is fastened at one end to a lug or cleat 24 near the inner edge of such lug or cleat. Such connection extends to and over one or more 80 small pulleys 37 and thence around another pulley 38 and through an opening in the head 33 and there secured. Each lug or cleat is provided with a flexible connection 36 arranged as described. Each set of 90 pulleys 37 is secured to a bracket 37^a securely affixed to the web 14 adjacent to the rim 12, and each pulley 38 is secured to a bracket 39 affixed to said web adjacent to the flange 15 of the hub 13.
- 40 indicates two flexible connections—preferably steel cables—each affixed at one end to oppositely located ears 41 projecting from the face of the plate 35 that is connected with the thimble 34. Such cables pass around a pulley 42 which is here shown as pivotally mounted on the axle 11, and at their forward ends they are connected with a lever 43 mounted on a suitable portion of the framework within 100 easy reach of the driver of the machine. As shown in Fig. 1, two sets of the cables 40 will be provided, one set for each wheel, and each set running around its own roller 42, but both sets will be secured to the operating lever 43 so that the mechanism of both wheels that is operated by means of a pull on the cables 40 will be moved simultaneously. It will be understood, of course, that the operating lever will be provided 110 with the usual spring latch or dog that engages in a notched segment alongside of the lever as usual.
- With a tractor having wheels provided with radially disposed lugs or cleats arranged as herein shown and described, it is evident that with such lugs or cleats in their retracted position as in Fig. 1, the machine can be moved over a road or other surface with no damage to such surface other than 120
- 130

such as would be caused by the mere weight of the machine alone, for the ridges of the resilient tire are all that make contact with the surface of the road. At such times the 5 lugs or cleats will be positively held in their retracted position by the action of the coiled springs 27. When, however, it is desired to make use of the lugs or cleats for greater traction all that is necessary to be 10 done to cause them to move outward into operative position is for the driver, by means of the lever 43, to exert a pull on the cables 40 which will cause the thimbles 34 and the heads 33 that are rotatably mount- 15 ed thereon respectively to be moved along the axle 11 and through the short cables 36 that are connected respectively with the various lugs or cleats such lugs or cleats will be forced outward against the power of 20 their respective springs. The driver, of course, can regulate the extent to which the cleats shall be projected by the extent to which he moves the lever 43, and when projected to the desired extent they will be 25 locked in such position by the locking of the lever to its segment. The head 33 on each wheel will be guided in its movements in and out not only by the axle 11 but by the various bolts 16, which, as stated, have a 30 sliding fit in the holes in the head and by reason of such engagement with the bolts will rotate with the wheel, while the thimble, by reason of being keyed to the axle, will be prevented from axial movements. 35 While I have referred to the head being movable back and forth on the axle, which, broadly speaking, is the case, it is of course to be understood that the head, while surrounding the axle, is not in actual contact 40 therewith, but has the non-rotating thimble interposed between it and the axle.

What I claim as my invention and desire to secure by Letters Patent, is—

1. In a vehicle, the combination of a 45 frame, an axle, a supporting wheel journaled on said axle, a plurality of cleats movably mounted in openings in the rim of said wheel, a member slidably mounted on said axle and movable toward and from the 50 hub of the wheel, a flexible connection extending from each cleat to said member, guides carried by the wheel and around which said flexible connections pass, and means carried by the frame for sliding said 55 member along the axle to cause the cleats to be forced outward beyond the rim of the wheel.

2. In a vehicle, the combination of a

frame, an axle, a supporting wheel journaled on said axle and comprising a rim, 60 a flanged hub and a web extending between the rim and hub, bolts connecting said web to the flange of the hub, a head slidably mounted on the axle and also on projecting end portions of said bolts, means carried by 65 the frame for moving said head on said axle and bolts, a plurality of cleats movably mounted in openings through the rim of the wheel, and means connecting each cleat with said head to cause their projection 70 when said head is moved in one direction.

3. In a vehicle, the combination of a frame, an axle, a supporting wheel journaled on said axle and comprising a rim and 75 a flanged hub connected together, a plurality of rods projecting from the inner face of the flange of the hub and parallel with the axle, a head slidably mounted on the axle and on said rods, means carried by the 80 frame for sliding said head along said axle and rods, a plurality of cleats movably mounted in openings through the rim of the wheel, and means connecting each cleat with said head to cause their projection beyond 85 the rim when said head is moved in one direction.

4. In a vehicle, the combination of a frame, an axle, a supporting wheel journaled on said axle and comprising a rim and 90 a flanged hub connected together, a plurality of rods projecting from the inner face of the flange of the hub and parallel with the axle, a head slidably mounted on the axle and on said rods, means carried by 95 the frame for sliding said head along said axle and rods, a plurality of cleats movably mounted in openings through the rim of the wheel, means connecting each cleat with said head to cause their projection beyond the 100 rim when said head is moved in one direction, and other means tending to normally hold said cleats retracted.

5. In a vehicle, the combination of a frame, a supporting wheel therefor, a plurality of cleats movably supported in openings in the rim of the wheel, means for simultaneously moving said cleats outward through said openings, a tire on said rim provided on its outer face with transverse recesses having openings therethrough in registry with the openings in the rim, and strips secured in said recesses provided also with openings in registry with the said openings in the tire and rim.

EDWARD P. CALDWELL.
